UNITED STATES PATENT OFFICE.

GOTTLIEB A. SCHLIENTZ, OF WINFIELD JUNCTION, NEW YORK.

IMPROVEMENT IN FOLDING CHAIRS.

Specification forming part of Letters Patent No. 155,758, dated October 6, 1874; application filed August 19, 1874.

To all whom it may concern:

Be it known that I, GOTTLIEB A. SCHLIENTZ, of Winfield Junction, in the county of Queens and State of New York, have invented a new and useful Improvement in Folding Chairs, of which the following is a specification:

This invention consists in a chair constructed of a seat and back which are pivoted to each other, slotted, and combined with cross-legs, back rails, and arms, operating in such a manner that the back can be inclined to any degree, and that a chair is obtained which is neat and strong, while it folds and unfolds with great ease and facility.

This invention is illustrated in the accompanying drawing, in which Figure 1 is a side view when unfolded. Fig. 2 is a vertical central section of the same. Fig. 3 is a side view when folded.

Similar letters indicate corresponding parts.

The letter A designates the seat, and B the back, which are pivoted to each other at a, which is at their inner ends, while near their outer ends they are provided with slots b b, working on pivots c c. These pivots are secured to the hind cross-legs C and to the back-rails D, which legs and rails are pivoted to each other at d. E are the front cross-legs, which are pivoted to the hind legs at e. To the upper end of the front cross-legs E are pivoted the chair-arms F, which are each provided with a slot, f, working on pivots g, which are secured to the back rails. The slots f are

provided with lateral notches or stops h, which fit the pivots i and serve to regulate the inclination of the back, a different notch being made to engage the pivots for a different inclination. The arms act upon the back rails, and through them the back is inclined.

To fold the chair, a slight pressure is first exerted on the front end of the arms E, whereby the stops h are disengaged from their pivot, and at the same time the back rail and back are thrown forward, the pivot e of the back rail sliding in its slot in the back. The cross-legs can then be readily folded together, and with the hind cross-leg is folded the seat, the pivot b of this leg working in its slot in the seat, while the cross-legs and seat are brought against the back rail and back, as shown in Fig. 3.

What I claim as new, and desire to secure by Letters Patent, is—

The seat A and back B, pivoted to each other and provided with slots b b, which work on pivots c c, in combination with cross-legs C E, arms F, and back rails D, arranged and operating substantially as described.

In testimony that I claim the foregoing I have hereunto set my hand and seal this 12th day of August, 1874.

GOTTLIEB A. SCHLIENTZ. [L. S.]
